United States Patent Office

Des. 211,783

Patented July 30, 1968

211,783

TORNADO SHELTER

Lee A. Turner, 6339 Nelwood Road,
Cleveland, Ohio 44130

Filed Nov. 24, 1967, Ser. No. 9,527

Term of patent 14 years

(Cl. D13—1)

FIG. 1

FIG. 2

FIG. 1 is an elevational view of a tornado shelter, showing my new design; and

FIG. 2 is a top plan view thereof.

I claim:

The ornamental design for a tornado shelter, as shown.
